FRITZ RICHARD DEURING, OF MUNICH-GLADBACH, GERMANY.

FEED AND TRAVERSING MOTION FOR LATHES.

Application filed January 14, 1924, Serial No. 685,959; and in Germany March 24, 1923.

A known device for traversing tool holders in capstan lathes, semi-automatic lathes and the like comprises a cam cylinder whose number of revolutions bears a definite relation to the number of revolutions made by a cam cylinder forming part of the slide feed motion, say 1:4. With this device the cam way for reciprocating the cross slide must be confined to a very small portion of the cylinder surface, and its curvature must be much steeper than that of the feed motion cam. The steepness of the cam involves loss of power and may give rise to seizing, so that the cross slide has a jerky motion, which is highly detrimental. Another disadvantage of the additional cam cylinder is that for changing over the traversing motion, from one side to the other, considerable time is required.

Another known method consists in an arrangement by which the turret slide imparts movement, at intervals, to a rack bar moving the cross slide. A rack used for the feed of the turret slide has had fixed to it a member embracing a cylindrical body coupled with a rack for feeding the cross slide, and the cylindrical body is coupled at intervals with the embracing member, but slides through it when not so coupled. This device works well, but the mechanism is somewhat expensive, and is not quite easy to understand by the ordinary workman.

The object of the invention is to remove these disadvantages. The invention consists in improved feed motion mechanism, which will be described with reference to examples thereof, shown in the annexed drawings, the distinctive features being pointed out in the subjoined claims.

Two forms of construction are shown in the drawings, in Figs. 1 and 2 and in Fig. 3 respectively.

Fig. 1 is a side view, partly in section, and Fig. 2 is a cross section on the line *a*—*b*.

Fig. 3 is a side view, partly in section.

Fig. 4 is an elevation showing the arrangement of the device in relation to the saddle and the cross slide.

Fig. 5 is a side view of a cam device for reciprocating the turret slide rack, and

Fig. 6 is a cross-section thereof.

Referring first to Figs. 1 and 2, 1 designates a reciprocating rack for moving the turret slide, and 2 is a rack in front of it, for moving the cross-slide. A lever 3 is pivoted at 5 to the rack 1, and lies within an

aperture 13 in the rack 2, so that it can move with the rack 1 unimpeded by the rack 2. The lever has a recess, in which two discs 4 each having a tooth 14, are mounted rotatably on a pivot 12.

The two discs 4 are spaced apart and are connected with each other by four pins 6, which are spaced uniformly around the pivot, like the staves of a lantern wheel. A spring 7 fixed to the lever and bearing against these pins imposes restraint on rotation of the discs and tends to retain them in any one of four positions to which they can be set. On the rack 2 there is an abutment 10, and each time the rack 1 moves to the left, as viewed in Fig. 1, one of the pins 6 strikes this abutment, causing the discs 4 to rotate one step. At each fourth step the discs occupy the position shown in Fig. 1, with the teeth 14 directed downwards, so that the lever 3 is lifted. By this means a tooth 15 of the lever is so placed that in the course of the following movement of the rack 1 to the right it will strike an abutment 8 connected to the rack 2. The rack 2 is thus moved. The next movement of the rack 1 to the left causes the discs 4 to be rotated another step, so that the lever 3 is dropped again, and put out of action. The abutment 8 is adjustable on a spindle 9 carried by the rack 2, the spindle having a screw thread engaging the abutment, so that by turning it the abutment can be shifted lengthwise of the rack 2, according to the movement which the rack is to receive.

Fig. 4 shows the application of the present invention to a lathe of known design. It will be noted from this figure that rack 2 engages a pinion *c* at the lower end of a vertical spindle, which has at its upper end a pinion *f* engaging a rack on a cross slide *d* moving between the guides *e*. After the rack 2 has been carried to the right, due to the engagement of the lever 3 with the abutment 8, upon the next movement of the reciprocating rack 1 to the left, the rounded head *a* of the lever 3 will engage in the recess *b* at the left end of the aperture 13, so that the rack 2 is restored to its left end position. The disk 4 at the same time is rotated another step due to the presence of the abutment 10 so that the lever 3 is dropped again and put out of action.

Figs. 5 and 6 show the device for periodically reciprocating the rack 1, which in certain cases may also be provided with teeth

if it is to be used for moving other parts. Behind the rack 1 is arranged a worm wheel 23 rotatable about the axle 22, the worm wheel being continually rotated by the worm 5 24. The side of the worm wheel toward the rack 1 is provided with a curved track 25. The rack 1 carries two rollers 26 and 27 which are alternately engaged by the track 25, and thereby cause displacement of the 10 rack 1 to the right or to the left. The rack 1 which lies in front of the worm wheel 23 is shown in dotted lines in Fig. 5, together with the rollers which it carries. When the worm wheel is rotated in the direction of the 15 arrow 28 the roller 26 is engaged by the track, and the rack 1 is moved to the left until the switch member 4 strikes against the nose 10 and is rotated 90° thereby. Toward the end of this movement the roller 20 26 has moved through the curved track to its break, that is, it has moved one-half way through the track. Upon further rotation of the worm wheel the track moves the roller 26 backward so that the rack 1 is returned 25 to its initial position. When the worm wheel rotates further the track comes into engagement with roller 27 and the above movement is repeated. During one rotation of the worm wheel therefore, the rack is moved 30 forward and backward twice.

In the modification shown in Fig. 3 the rack 1 carries on a pivot 12' a ratchet wheel 4' having a circular series of holes 16, into which pins or studs 17 can be inserted, say 35 four studs, as shown, or any other number up to the number of holes provided. The rack 2 carries a pawl 10' engaging the ratchet wheel. A lever 3' is pivoted at 5' to the rack 1. The left hand arm of this 40 lever, as viewed in Fig. 3, is weighted so that it tends to lift a projection 19 on the other arm into the path of the studs 17. When one of the studs 17 strikes the part 19, the right hand arm of the lever is depressed. 45 When it has been depressed, as shown in the drawing, and the rack 1 moves in the direc-

tion of the arrow 20 the lever strikes an adjustable abutment 8' on the rack 2 and moves the latter. When the rack 1 moves in the direction of the arrow 21 the ratchet 50 wheel 4' strikes the pawl 10' and is rotated one step, so that the stud 17 which was resting on the part 19 is removed therefrom, and the weighted arm of the lever is allowed to drop on the bottom edge of the aperture 55 13 in the rack 2. When the rack 1 is approaching the end of its leftward movement the lever 3' strikes the adjacent upright edge of the aperture 13 and moves the rack 2 back to its former position. The following movements of the rack 1 will not cause movement of the rack 2 until after the next stud 17 has depressed the lever 3' again.

It will be understood that the mechanism shown can be modified in detail in many respects without departing from the principle of the invention.

What I claim is:

1. Feed motion mechanism for lathes having 70 turret slides and cross slides, comprising two reciprocable racks for moving the turret slide and the cross slide respectively, means for reciprocating said turret slide rack, a catch pivoted to one of said racks, an abutment carried by the other rack, a member rotated stepwise by reciprocation of said turret slide rack, said rotatable member having means for moving said catch into position to engage said abutment in one position thereof, whereby said cross slide rack will 75 be moved with said turret slide rack.

2. Feed motion mechanism as claimed in 80 claim 1, wherein the pivoted catch is a lever pivoted to the turret slide rack and disposed within an aperture in the cross-slide rack, the rotatable member being pivoted to said lever and being rotated stepwise by striking an abutment within said aperture.

The foregoing specification signed at Cologne, Germany, this 19th day of November, 90 1923.

FRITZ RICHARD DEURING.
